CLAIM

The ornamental design for pulley housing, as shown and described.

DESCRIPTION

FIG. 1 is a top, front, left perspective view of a pulley housing showing our new design with selected features disclaimed;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof;

FIG. 8 is a bottom, rear, right perspective view thereof; and, FIG. 9 is a top, front, left perspective view thereof, showing our new design in its exemplary environment.

The broken lines showing the remainder of the pulley housing and the exemplary environment show features that form no part of the claimed design.

1 Claim, 7 Drawing Sheets# US D893,639 S
